UNITED STATES PATENT OFFICE

2,490,527

CONCRETE FLOOR FORM

James Ledbetter, Miami, Fla.

Application March 7, 1947, Serial No. 733,029

2 Claims. (Cl. 25—131.5)

1

The invention relates to improvements in building construction, particularly to building construction in which pre-cast and poured cement are used together, but more particularly to the use of pre-cast joists with poured floors; and has for its objects the development of a form of construction and method of assembly which will be simple of structure, easy to construct and highly efficient in use.

This invention and this application further relate to a joint application, Serial Number 678,383, filed June 21, 1946, for Building construction, and still pending.

Other objects will appear hereinafter.

The invention consists in the combinations and arrangements of parts hereinafter described and claimed.

The invention will be best understood by reference to the accompanying drawings forming a part of this specification, and in which

Figure 1 is a vertical section of my improved floor construction, illustrating the arrangement of the supporting forms and the releasable means by which they are supported, and a cross section of the pre-cast joists used; and

Figure 2 is a ceiling plan view of Figure 1.

The embodiment of the invention illustrated in the drawings comprises pre-cast joists 15 arranged in suitably spaced relation, with the ends thereof resting on a suitable wall 16. Each joist 15 is provided with an offset upper portion 17 on each of its faces 18 forming floor supporting ledges 19, and is further provided with 2 reinforcing steel rods 20 set adjacent the lower edge thereof. The joists 15 are provided, at a short distance above the said rods 20 with vertical slots 21 therethrough, having openings on each face 18 and are spaced at suitable distance apart throughout the length thereof, being adapted to serve as mounting means for cooperating key members 22. The key members 22 are used in pairs inserted in the slots 21 from opposite sides of the joists 15, as best shown in Figure 1. Each key member 22 is constructed from steel plate of even thickness and is substantially L-shaped with a wedge shaped stem portion 23 and a short arm portion 24 arranged at right angle to the lower edge of the stem, as used. When in use in the slots 21 the stem portions are overlapped at each end, the overlapped portion being provided with a hole adapted to receive a pin 25, which serves as locking means when a pair of key members 22 are arranged in a slot 21. The arrangement is such that when a joist 15 is equipped with the key member 25, a plurality

2

of hooks are formed by the short arm portions 24 protruding from a face 18, and are arranged and adapted to hold a steel ledge bar 26 which extends the full length of the joist face 18 in position to serve as removable shoulders for supporting steel arch plates 31 and 32, as best shown in Figure 1. The arch plate 31 is provided with an angular lip portion 33 at its upper edge, which is adapted to be inserted in groove 34 formed by a channel bar 35 riveted to the upper portion of the arch plate 32, as shown. Each of the arch plates 31 and 32 are provided with lap bars 36 for reinforcing and providing a lap surface for the next adjoining arch plate, as will be readily understood.

The arrangement is such that after the pre-cast joists 15 are set in desired position, a pair of key members 22 is placed in each of the slots 21 with ledge bars 26 resting thereon. The arch plates 31 and 32 are then assembled in arched position, the key members 22 driven into place and pin 25 inserted. The floor 37 can then be poured. After the poured cement has set to the desired state of curing, the assembled form parts can be easily and quickly dropped by releasing the key members 22. The slots 21 which have served for the key members 22 can then be closed by patching with cement, or left for the placing of electrical wires or the like, if so desired.

While I have illustrated and described a precise arrangement for carrying my invention into effect, this is capable of variations and modifications. I, therefore, do not wish to be limited to the construction shown, but desire to avail myself of such changes as may fall within the scope of the appended claims.

I claim:

1. A mold for an arched floor construction arranged between pre-cast concrete joists, each of said joists being provided with a plurality of longitudinally aligned vertically extending slots there through; which comprises a pair of key member support elements arranged in opposed and slidable position within each slot, a vertically arranged arm on each key member arranged in parallel clamping relation with a wall of a joist; means for mutually holding said vertically arranged arms in parallel relation with each side of a joist; a longitudinal support mounted against each side of a joist and held by said arms arranged and adapted to support a pair of companion arch plates, and a pair of companion arch plates mounted on said support.

2. The construction, specified in claim 1 in which the companion arch plates are arranged

in a substantially V shape with their bottom edges resting on the longitudinal supports carried on the vertical arms.

JAMES LEDBETTER.
